UNITED STATES PATENT OFFICE.

EDWARD B. CRAFT, OF CHICAGO, ILLINOIS, ASSIGNOR TO WESTERN ELECTRIC COMPANY,
OF CHICAGO, ILLINOIS, A CORPORATION OF ILLINOIS.

COIN-COLLECTOR.

No. 884,470.

Specification of Letters Patent. Patented April 14, 1908.

Application filed February 13, 1906. Serial No. 300,882.

To all whom it may concern:

Be it known that I, EDWARD B. CRAFT, citizen of the United States, residing at Chicago, in the county of Cook and State of Illinois, have invented a certain new and useful Improvement in Coin-Collectors, of which the following is a full, clear, concise, and exact description.

My invention relates to a toll box for telephone pay stations, and has for its object to provide an improved organization of apparatus wherein a count or record is kept upon a register of each coin deposited.

More particularly, my invention is applicable to coin collectors where a plurality of coins of predetermined size are required of a subscriber in order to obtain a desired connection, and my aim is to provide means for refunding such coins without affecting the register, and to deposit such coins one at a time, the register being operated each time a coin is deposited. In applying my invention to such a system, I provide a temporary coin receiver adapted to simultaneously support a plurality of coins required of the subscriber, electromagnetic mechanism being provided adapted when suitably operated to discharge said coins one at a time into a cash box, said mechanism, each time a coin is deposited, operating a register to record the deposit. Said mechanism is also adapted when properly operated to simultaneously discharge said coins into a refund tray without affecting the register.

I will describe my invention more particularly by reference to the accompanying drawings which illustrate an embodiment thereof, reserving for the appended claims a statement of the parts, improvements and combinations which I deem novel with me.

Figure 1 is a front view of a toll box embodying my invention, as indicated by line 1-1 of Fig. 2, with the cover removed, and showing in dotted lines the relative positions of the coins on the guide rail; Fig. 2 is a side elevation with the cover in section; Fig. 3 is a detail plan sectional view, showing the connection of the register with the armature; Fig. 4 is a detail plan sectional view, showing the guide; and Fig. 5 is a detail side elevation of the guide and rail, showing the same about to deposit a coin.

The same letters of reference indicate the same parts wherever shown.

The toll box shown in the drawing is 55 adapted for use where three coins of a predetermined size are required to be deposited by a calling subscriber in order to obtain a desired connection. The coin chute *a* leads from an opening in the side wall of the box to 60 a downwardly inclined guide rail *b*, preferably grooved to prevent the coins from slipping off, and on which the first coin rolls until it strikes a stop *b'* at the end of the rail. A movable grooved guide or discharge arm 65 *c* is adapted to receive the tops of the coins on said rail. The coins are held on the rail *b* end to end, stops *d* being automatically interposed by said coins between themselves to prevent wedging thereof, said coins being 70 adapted when on said rail to operate contacts in the usual manner. The rail *b* and guide *c* form a temporary receiver for the coins inserted in the box by the subscriber. The guide *c* is in two parts, *c'*, *c''*, the part *c'* being 75 over the lower end of the rail and arranged to support a single coin. The part *c'* is connected by a bar *e* with the tilting armature *f'* of a polarized electromagnet *f*, the other part being connected by a bar *e'* with a cross bar *e''* pivoted to the frame. Said armature is also connected with the operating pawl *g'* of a register *g*. The armature *f'* is adapted when tilted by the magnet in the direction indicated in Fig. 5 to move the part *c'* of the 80 guide arm and throw the coin held thereby into a chute *h'* leading to the cash box *h*, the armature at the same time operating the pawl *g'* to advance the train of the register and make a record of the deposit. The part 85 *c'* carries an arresting finger *c''*, which while the part *c'* is moved away from its normal position in alignment with the part *c''*, to deposit the coin, lies in front of the next coin on the rail to prevent it from passing on to the 90 end of the rail. As soon, however, as the part *c'* reaches its normal position, the said next coin on the rail rolls down into the control of the depositing part *c'* and is deposited, the register being again operated. The depositing part *c'* carries a finger *c''* which when the part *c'* is moved by the armature *f'* of the polarized magnet in a direction opposite to that indicated in Fig. 5, is adapted to engage the part *c''*, thereby simultaneously 95 discharging the coins held by both parts *c', c''*, into a refund chute *i'* leading to a refund tray on the outside of the box, without 100 105

affecting the register, the pawl g' being by such movement of the armature moved away from the registering train.

The chute a and guide rail b may be laterally inclined toward the refund chute, as shown, so that coins of less than the predetermined size will be automatically discharged into the chute leading to the refund tray.

10 It will be noted that the coin distributing mechanism and register are in a locked compartment independent of the locked compartment containing the cash box, so that the collector, who has the key to the cash box compartment, cannot obtain access to the register and falsify the count. The provision of the register provides a check on the collector.

I provide spring-actuated means for returning the armature and parts c' , c^2 , of the guide to normal position, the part c^2 when in such position resting against a stop e^3 which prevents it from moving in a direction to deposit the coin held thereby.

25 I claim:

1. In a coin collector, the combination with a temporary receiver for a plurality of coins, deposit and refund chutes, electromagnetic mechanism for discharging said coins into said refund chute, said mechanism being also adapted to discharge said coins one at a time into said deposit chute, and a register operated each time a coin is thrown into said deposit chute.

35 2. In a coin collector, the combination with a coin chute, of deposit and refund chutes, a guide rail adapted to receive coins from said chute and simultaneously support a plurality thereof, supporting means for the tops of said coins, electromagnetic mechanism adapted to operate said supporting means to discharge said coins one at a time into said deposit chute, and a register operated by said mechanism as each coin is deposited, said mechanism being also adapted to discharge said coins into the refund chute without affecting said register.

3. In a coin collector, the combination with a coin chute, of deposit and refund chutes, a guide rail adapted to receive a plurality of coins from said chute, a movable support for the tops of said coins, an electromagnet adapted to operate said support to throw said coins one at a time into said deposit chute, and a register operated by said magnet each time a coin is deposited, said magnet being also adapted to operate said support to throw said coins simultaneously into the refund chute.

60 4. In a coin collector, the combination with a coin chute, of deposit and refund chutes, a guide rail adapted to receive and simultaneously support a plurality of coins from said chute, a two part movable guide adapted to engage the tops of said coins,

electromagnetic mechanism for moving both parts to discharge said coins simultaneously from the rail into the refund chute, said mechanism being adapted to move one of said parts alone to deposit the single coin supported thereby, the remaining coins thereupon passing singly under the control of said part, and a register operated by said mechanism upon the deposit of each coin.

5. In a coin collector, the combination with a coin chute, of a downwardly inclined guide rail adapted to receive and simultaneously support a plurality of coins from said chute, a movable guide adapted to engage the tops of said coins, deposit and refund chutes on opposite sides of said rails, said guide being in two parts, electromagnetic mechanism for moving one of said parts which engages a single coin, said electromagnetically-operated part when moved in one direction engaging the other part to throw all said coins simultaneously into said refund chute, said first mentioned part when moved in the other direction depositing the coin supported thereby without disturbing said other part, the remaining coins rolling one at a time under the control of said depositing part, and a register operated by said electromagnetic mechanism only as each coin is deposited.

6. In a coin collector, the combination with a coin chute, of deposit and refund chutes, a guide rail adapted to receive a plurality of coins from said chute, a two-part movable guide adapted to engage the tops of said coins, a polarized electromagnet, a tilting armature for said polarized magnet connected with one of said parts and adapted when moved in one direction to cause said part to deposit the single coin engaged thereby, the remaining coins thereupon passing singly under the control of said depositing part and being singly deposited, said armature when moved in the opposite direction causing said depositing part to engage and move said other part to throw the coins held by both parts simultaneously into the refund chute, a register, and an operating pawl therefor connected with said armature to operate the register only when the armature is tilted in the direction to deposit a coin.

7. In a coin collector, the combination with a coin chute, of a downwardly inclined guide rail adapted to receive and simultaneously support a plurality of coins end to end, deposit and refund chutes on opposite sides of said rails, a two part movable guide engaging the tops of said coins, electromagnetic mechanism adapted to move one of said parts alone in a direction to throw the single coin supported thereby into said deposit chute, an arresting finger carried by said depositing part and presented before the other part while the depositing part is operating alone, to prevent the remaining coins from leaving said other part, said remaining coins when

the depositing part returns to normal position rolling singly into the control of said depositing part and being singly deposited, a finger carried by said depositing part and adapted to engage said other part, said mechanism being adapted to move said depositing part in the opposite direction and cause said finger to move the other part, to simultaneously discharge the coins held by both parts of said guide into the refund tray, and a reg-

ister operated by said electromagnetic mechanism as each coin is deposited, but remaining inert when the coins are refunded thereby.

In witness whereof, I, hereunto subscribe my name this 6th day of February A. D., 1906. 15

EDWARD B. CRAFT.
